FIG. 2

This technical drawing illustrates a headgear assembly, likely a chin strap system. The main component is a curved strap with a central chin cup. The chin cup is secured to the strap with a central fastener, indicated by a dashed circle with the number 12. The strap is attached to two vertical panels, each featuring a circular fastener, labeled 26, and a rectangular fastener, labeled 24. The drawing also shows two vertical panels, labeled 13, which are part of the headgear structure. The entire assembly is shown in a perspective view, highlighting the curved shape of the strap and the attachment points.

FIG. 3

INVENTOR
Joseph Bijur,
Henry G. Davis

ATTORNEY

UNITED STATES PATENT OFFICE.

JOSEPH BIJUR, OF NEW YORK, N. Y., ASSIGNOR, BY MESNE ASSIGNMENTS, TO
ECLIPSE MACHINE COMPANY, OF ELMIRA HEIGHTS, NEW YORK, A CORPORATION
OF NEW YORK.

ENGINE-STARTING APPARATUS.

Application filed October 2, 1919, Serial No. 327,920. Renewed October 2, 1924.

To all whom it may concern:

Be it known that I, JOSEPH BIJUR, a citizen of the United States, residing at New York city, in the county of New York and 5 State of New York, have invented certain new and useful Improvements in Engine-Starting Apparatus, of which the following is a clear and exact description, such as will enable others skilled in the art to which it 10 appertains to make and use the same.

This invention relates to engine starting apparatus more especially to such as are employed for starting automotive engines, and the invention has particular application to 15 aviation engines.

One of the objects is to provide apparatus for starting a source of power which apparatus shall be of compact and durable construction as well as reliable in action.

20 Another object is to provide apparatus of the type referred to which shall be easy of application to aviation engines, particularly to such as are not designed to carry starters and in which the available space is inadequate for ready mounting of types of starters heretofore used on automobile engines. The invention has especial utility for starting the United States Liberty engine, though it has a much broader field of application.

30 Other objects will be in part obvious and in part pointed out hereinafter.

The invention accordingly consists in the features of construction, combinations of elements and arrangement of parts which 35 will be exemplified in the construction hereinafter set forth, and the scope of the application of which will be indicated in the following claims.

In the accompanying drawings wherein is 40 shown one of various possible embodiments of the several features of this invention, Fig. 1 is a view in longitudinal section of my starter as applied to the engine, the pinion being shown out of mesh, Fig. 2 is a fragmentary view showing the pinion in butting position and the shifting mechanism biased to relieve the butt, Fig. 3 is a fragmentary front view of the starter unit, Fig. 4 is a detail sectional view taken along line 4-4 45 of Fig. 1 and Fig. 5 is a fragmentary view of the pinion and its mount in isometric perspective.

Similar reference characters refer to similar parts throughout the different views of 55 the drawings.

Referring now to the accompanying drawings I have shown a fragment of the "nose" 1 of an engine, which I define as that part of the crankcase in advance of the cylinder base 2. The proportions shown are illustratively those of the Liberty engine. Other details of this engine are not material to this invention and are, therefore, not shown. At the forward end of the crankshaft 3 is a hub 4 for the usual propeller or airscrew a fragment of which is shown at 5. Secured to the propeller hub by means of bolts 6 I provide a ring 7 having spur gear teeth 8 at its periphery through which the torque of the starting motor is applied to the engine. 60 The specific construction of the gear ring 7 and its application and manner of use constitute no part of the invention claimed herein and the description thereof need not, therefore, be given in greater detail. This 65 subject-matter is fully described and claimed in my copending application Serial No. 224,494 filed March 25th, 1918, now Patent 1,429,670.

In the following description of my starting apparatus, I will designate the end adjacent gear ring 7 as the forward or front end, and the opposite as the rear end.

To apply the torque at the gear teeth 8 on the ring 7 I provide an electric starting motor M connected to rotate a coaxial toothed driving member or pinion 9 the teeth 10 of which are preferably chamfered as at 11. The pinion is normally displaced from the gear 7 but adapted preferably through the agency of automatic shifting mechanism to be brought into mesh therewith. By reason of the restricted length of the nose of an engine of the type referred to, which in the relatively large Liberty 95 engine, for instance, is but seven inches, the shifting mechanism has a telescoped relation to the length of the motor so that the over-all length of motor and shifting mechanism is sufficiently small to render possible 100 the disposition of the starting unit, comprising the motor, shifting mechanism and pinion in the limited space available.

The starting unit is preferably held in proper alignment with the gear ring 7 by 105 lodging the cylindrical surface of its yoke 12 in a corresponding seat in a cradle 13. The rear of cradle 13 has a pair of lugs 14 fitting upon corresponding bosses 15 110 formed as regular parts of the construction

of the engine, a pair of bolts 16 constituting a part of the engine construction passing each through one said boss and the corresponding lug and having nuts 17 threaded and locked one to the end of each to firmly secure the lugs 14 upon the engine. Similar lugs 18 are provided at the other end of the cradle resting upon a channel shaped platform 19, a pair of bosses 20 on the engine 10 forming a support for said platform and bolts 21 securing said platform to the engine. The height of the platform is such as to bring its supporting surface 22 on a level with the bottom of lugs 14 so that lugs 18 15 may rest upon said surface 22 and may be secured thereto by bolts as at 23.

The yoke 12 of the motor is preferably provided with two pairs of radial studs 24 adapted to register with corresponding 20 notches 25 cut into the opposite edges of the cradle 13, lock nuts 26 serving to secure said studs with respect to the cradle. It is seen that the motor can thus be readily applied to the engine, the radial studs passing along and into the slots as the motor is laid upon its cradle and being readily removable therefrom after the nuts 26 are removed.

Within the yoke 12 of the motor is secured a stator or field construction 27 within which is mounted a rotor in the form of an armature 28 disposed between end heads 29 and 30 telescoped over the yoke, and held together preferably by bolts 31. The armature 35 is preferably provided with a relatively large axial opening 32, the laminations 33 of its core 34 fitting over a hollow shell 35 and being held against rotation thereon by means of a key 36 preferably welded into 40 a depression 36' in the shell and fitting into a registering notch 37 in each of the laminations, said notches constituting a key way in the core. The laminations of the core are firmly held against separation between 45 a shoulder 38 on the shell in contact with an insulation piece 39 at one end of the armature core and a lock ring 40 fitting into a groove in shell 35 and pressing against a washer 41 at the other end of the core. The armature windings 42 fit into slots in the core, in the well-understood manner and are connected to the usual commutator 43 built upon the end of the shell 35.

For mounting the armature in proper 55 assembled relation between the heads 29 and 30 I provide the heads respectively with central bearings 44 and 45 extending respectively into inwardly extending hubs 46 and 47. About hub 46 I dispose a ball bearing 60 48 for supporting one end of the armature shell 35. A slideable shaft 49 extends through bearing 44 and supports one end of the shell 35 which latter has an inwardly extending flange 50 that surrounds a bushing 51 about the rear end of the shaft. The

bushing 51 extends into bearing 45 and is held against longitudinal movement by an integral flange 52 abutting shell flange 50 and a washer 53 fitting into a groove 54 in the bushing and between flange 50 and the bearing 45. It is seen that the pinion carrying shaft 49 completely closes the opening to the shell at each end of the armature, thus preventing entry of dust or dirt into the mechanical shifting mechanism enclosed 75

The pinion 9 is preferably mounted upon the forward end of the shaft by means of a bolt 55 passing axially through the pinion and into the forward end of the shaft and threaded at its inner end as at 56. A taper pin 57 is seated in a depression in the shaft as at 58 and fits in the bifurcated end 59 of the bolt 55 so that when said bolt is screwed home to secure the pinion 9 against the end of the shaft, the taper pin will expand the threads to firmly tighten the pinion upon the end of the shaft. Cooperating radial splines 84 effect a positive drive between the shaft and the pinion. The pinion is thus 90 disposed on the outside of end head 29. The head is preferably formed with a concavity as shown in which the pinion is lodged, thus avoiding a lengthening of the starting unit 95 construction.

The transmission mechanism for shifting the pinion 9 to bring it into mesh with the teeth of the gear ring 7 and for then transmitting the cranking torque is preferably of the automatic type. The preferred construction shown on the drawings includes a clutch unit designated in its entirety by numeral 60 said unit comprising a nut 61 cooperating with threads 62 cut in the inner surface of shell 35; a clutch plate 63 having splines 64 interfitting corresponding splines 65 on shaft 49 and a clutch washer 66 of cork or the like interposed between said plate and the flange 67 on said nut, and secured to said plate by any appropriate means (not shown). The plate 63 may be provided with an extension 63' cooperating with splines 65. The extension 63' gives length to the bearing of plate 63 on the shaft 49 and splines 65 and thus prevents the clutch unit from tilting with reference to the shaft and thereby being cramped thereon. This extension 63' also supports the end of spring 69 clear of the shaft 49. Interposed between the clutch plate 63 and a flange 68 formed integrally with the shaft 49 I provide a relatively strong coil spring 69 which encircles the shaft 49 and urges the clutch unit against a stop nut 70 threaded upon the rear end of shaft 49. A dished spring washer 85 is preferably interposed between flange 68 and spring 69, said washer being of a stiffness less than that of the said spring. The spring 69 as is apparent, imparts an initial torque to the friction clutch 130

unit 60. The torque on the clutch is variable depending on the compression of spring 69 as will appear more fully below.

Upon the side of the nut flange 67 opposite that of clutch washer 66, I form a constant torque clutch the purpose of which will appear more fully below. This clutch comprises a clutch plate 71 splined to shaft 49 as at 72 and contacting the nut flange, 10 and a dished spring washer 73 fitting against the plate 71 and held in place under a fixed compression by a lock ring 74 fitting in a groove 75 in the nut 61. An annular washer 76 is preferably interposed between 15 the dished spring and the lock ring.

The transmission is preferably provided with a buffer mounted inside the shell 35 and comprising a nut 77 threaded into the shell, an impact washer 78 and a plurality 20 of dished spring steel washers 79 interposed between the nut 77 and the impact washer 78 and urging said impact washer against stops 80 preferably forming the ends of the screw-threads 62.

25 To prevent creeping movement of the pinion together with shaft 49 while the starter is not in use, a conical coil spring 81 is preferably provided, abutting the flange 68 on the shaft at its smaller end and fitting 30 into a retainer 83 annular in form at its larger end. The retainer is interposed between the ball bearing 48 and the shoulder 38' on the shell. Spring 81 resists the outward travel of the shaft 49 which, with the 35 pinion 9, therefore tends to rotate with the armature prior to meshing and the stiffness of the spring is preferably such that the pinion rotates through an angle of approximately ninety degrees during its advance 40 toward mesh, thereby reducing the chance of butting of teeth.

My starting motor may be assembled as follows: The spring 69 is first slipped over the rear end of the shaft 49 whereupon the 45 clutch assembly made up of clutch plate 63, clutch washer 66 and nut 61 and the constant torque clutch elements 71, 73, 74 and 76 is passed over the end of the shaft into cooperation with the splines 65 on said shaft. 50 Thereupon the stop nut 70 is threaded and locked onto the end of the shaft. The spring 81 being first passed over the forward end of the shaft, this shaft is inserted into the shell 55 of the armature, the nut entering into threaded cooperation with the threads 62 in said shell, the buffer construction 77, 78, 79 having been previously placed into the shell. The bushing 51 is then applied near the rear of the shaft and held in place by the washer 63. The ball bearing 48 being mounted 60 within the head 29, the two end heads may be placed in position and secured with respect to the yoke 12 by bolts 31. The pinion 9 may then be applied, the bolt 55 being 65 threaded in position and being locked there-

in by the wedging action of the taper pin 57 in the manner obvious from the description of the construction above.

In operation, the motor being assumed 70 mounted in position, a starting switch (not shown) preferably of the non-resistance type is closed to connect the motor with a source of current preferably a storage battery (not shown). The armature starts rapid rotation together with the threaded shell 75 35 which is an integral part thereof. The nut 61 being rotatable as a unit with the clutch elements, the shaft 49 and the pinion 9, the inertia of this assembly of parts will prevent the nut from immediately taking up 80 the rotation of the shaft. Consequently the nut will advance pushing shaft 49 and pinion 9 forwardly through the compression spring 69 against the resistance of spring 81, until the pinion is in mesh with teeth 8 on the gear ring 7. The action of spring 81 assures a slow rotation of the pinion as above pointed out, thus facilitating the meshing action. When the pinion is in 85 mesh, further advance of the shaft and pinion is strongly resisted by engagement of clutch plate 63 with impact plate 78 of the buffer. As the pinion 9 is now in cranking connection with gear ring 7, and the engine 90 resists rotation of the latter, the pinion will 95 tend to continue its advance together with its shaft, thus tightening the friction clutch 60 until the nut is compelled to rotate as a unit with the armature and its shell. If the 100 resistance of the engine to cranking is sufficiently high, the dished washers 79 may become partially or wholly compressed before the clutch 60 has the needed tightness for delivering the cranking torque. Cranking torque is thus yieldingly transmitted from 105 the shell 35 through the nut 61, the friction clutch assembly, the shaft 49 and the pinion 110 to the gear ring 7 on the engine.

When the engine starts under its own power, a rate of rotation is imparted to the 110 pinion 9 and its associated shaft 49 greater than the rate imparted to the shell by the motor. The nut consequently overruns the shell thus retiring to its original position 115 and by reason of its contact with the stop nut 70 the shaft 49 is also withdrawn thus drawing the pinion 9 out of mesh to the position shown in Fig. 1.

While the aeroplane or other vehicle 120 equipped with my starter is running the spring 81 resists any accidental undesired advance of the pinion 9 with shaft 49 into contact with the geared ring 7 and this regardless of the grade or roughness of the 125 course.

Meshing of the pinion with the gear ring 130 will ordinarily take place readily as the chamfered construction shown at 11 facilitates entry of the pinion teeth. Should, however, a pinion tooth impact a tooth of

the gear ring directly end to end so that the pinion and with it the shaft 49 are arrested in both their forward and rotary movement, thus preventing entry, then the nut 61 should advance along both the threads 62 in the shell and the splines 65 on the shaft, thereby compressing the spring 69 to tighten the clutch 60 until the nut commences rotating with the shell. A slight rotation of the shaft will be sufficient to bring the teeth of the pinion out of butting into meshing alignment with the gear teeth at which time rapid expansion of coil spring 69 will urge the pinion into full mesh with the gear ring, whereupon the normal cranking and demeshing will proceed as above described.

If the construction thus far described in the operation, alone were employed it might occur, immediately after butting of the teeth that the pressure exerted by the spring 69 does not impart sufficient torque to the clutch 60 to allow it to turn the pinion into meshing alignment, in which event the nut would rotate with the shell, therefore failing to advance, the clutch would slip, and the gears remain in butting condition as long as the motor was energized. This is prevented by the constant torque clutch 71-76 the holding power of which is added to that of the variable torque clutch to prevent a rotation of the nut with the armature even under the most severe conditions of but thus compelling advance of the nut, tightening of clutch 60 and relief of but in the manner above described. The constant torque clutch 71-76 thus assists the variable torque clutch to compel advance in butt relief when the latter is at its weakest. After the variable torque clutch has become tightened to a certain extent in the manner above set forth, the assistance of the constant torque clutch is no longer needed to cause further advance. In the construction shown, however, the constant torque clutch transmits a portion of the torque throughout the operation of the starter.

Although I have shown my starter in a preferred application to aviation engines it is to be understood that this starter is also applicable to engines for propelling other types of vehicles such as automobiles and motor boats, and that this invention is further applicable to the starting of stationary engines.

It is further to be noted that my starting unit may be mounted to cooperate with the end of the crank-shaft opposite the propeller, or with other parts of the engine and that other mounting means for this unit may be employed.

While I have shown a construction in which the screwthreads or inclined splines are on the shell and the straight splines on the shaft and although this is my preferred construction, it is to be understood that

beneficial results may be obtained by placing the screwthreads on the shaft and the straight splines on the shell as will be apparent from my copending application Serial No. 224,494 filed March 25th, 1918. 70

The construction for shifting and transmitting torque has certain features in common with that of my copending application Serial No. 145,839 filed February 1st, 1917, such common subject-matter being fully 75 claimed in the latter application and, therefore, not claimed herein.

It will thus be seen that there is herein described apparatus in which the several features of this invention are embodied, and 80 which apparatus in its action attains the various objects of the invention and is well suited to meet the requirements of practical use.

As many changes could be made in the 85 above construction and many apparently widely different embodiments of this invention could be made without departing from the scope thereof, it is intended that all matter contained in the above description or 90 shown in the accompanying drawings shall be interpreted as illustrative and not in a limiting sense.

Having thus described my invention, what I claim as new and desire to secure by Letters-Patent is:—

1. An engine starter, comprising in combination, a motor, a pinion adapted to be engaged with an engine, and shifting means for said pinion having a portion extending between the ends of the motor, said shifting means comprising an internally threaded shell, a splined, slidable shaft coaxial therewith, and a member cooperating with said threads and with said splines, said pinion 105 being on the end of said shaft.

2. The combination, in an engine starter, of a shell having inclined guide means, a splined, slidable shaft passing through said shell coaxially therewith, a pinion on said 110 shaft, shifting means for said pinion, comprising a member encircling said shaft and interfitting said guide means, and means transmitting torque to said pinion.

3. The combination, in an engine starter, 115 of a shell having inclined guide means, a splined, slidable shaft passing through said shell coaxially therewith, a pinion on said shaft, shifting means for said pinion, comprising a member encircling said shaft and 120 interfitting said guide means, and means transmitting torque to said pinion, said means including a self-tightening friction clutch.

4. The combination, in an engine starter, 125 of a shell having inclined guide means, a splined, slidable shaft passing therethrough, a pinion on said shaft, a control member co-acting with said guide means, a clutch plate encircling said shaft and interfitting the 130

splines thereof, and a friction clutch washer between said control member and said clutch plate.

5. The combination, in an engine starter, of a motor, a shell, and a slidable shaft passing therethrough, a driving pinion on one of the latter members, a clutch unit in threaded relation to said shell and in splined relation to said shaft, for causing advance 10 of the pinion carrying member to meshing position responsive to starting of the motor, said clutch then functioning to transmit the cranking torque.

6. The combination, in an engine starter, of a shell internally threaded, a splined, slidable shaft passing therethrough, a pinion mounted near the forward end of said shaft, a clutch unit in threaded relation to said shell and in splined relation to said 20 shaft whereby said clutch unit may move forwardly with respect to said shell, and means for transmitting the forward movement of said clutch to said shaft and for then transmitting the torque through said clutch.

25 7. The combination, in an engine starter, of a shell, a slidable shaft passing therethrough and having a pinion mounted near its forward end, a friction clutch unit in threaded relation to said shell and in splined 30 relation to said shaft, for causing advance of said shaft to mesh said pinion, and means to then tighten said clutch for cranking torque transmission.

8. The combination, in an engine starter, of a motor, a rotatable shell, a slidable shaft passing therethrough coaxially therewith, and having a toothed driving member near its forward end and shifting means connected between said shell and said shaft, and 40 including a spring for pushing said shaft forwardly for meshing of said pinion, responsive to starting of the motor.

9. The combination, in an engine starter, of a motor, a rotatable shell, a slidable shaft passing therethrough coaxially therewith and having a driving pinion near its forward end, and shifting means including a nut interposed between said shell and said shaft and threaded to one thereof, and a coil 50 spring in the path of said nut, and having a part of the shaft in its path, whereby upon starting of the motor the shaft will be spring pressed forwardly for mesh of said pinion.

10. The combination, in an engine starter, of a motor, a rotatable shell, a slidable shaft passing therethrough coaxially thereof, said shaft having a driving pinion near its forward end and a shoulder intermediate its ends, pinion shifting means including a 60 friction clutch unit interposed between said shell and said shaft, in threaded relation to one thereof and in splined relation to the other, and a coil spring encircling said shaft and interposed between said clutch unit and said shoulder.

11. The combination, in an engine starter, of a motor, a rotatable shell, a slidable shaft passing therethrough coaxially thereof, said shell having a driving pinion near its forward end and a shoulder intermediate its 70 ends, a friction clutch unit interposed between said shell and said shaft, and comprising a nut threaded into said shell, a clutch plate splined to said shaft and a washer of cork or the like interposed between one face of said nut and said plate, and a coil spring encircling said shaft and interposed between said plate and said shoulder.

12. The combination, in an engine starter, of a motor, a rotatable shell, a slidable shaft passing therethrough coaxially thereof, said shaft having a driving pinion near its forward end and a shoulder intermediate its 80 ends, a friction clutch unit interposed between said shell and said shaft, and comprising a nut threaded into said shell, a clutch plate splined to said shaft and a clutch washer interposed between one face of said nut and said plate, a coil spring 90 encircling said shaft and interposed between said plate and said shoulder, and a plurality of annular dished washers in said shell and adapted to yieldingly arrest said plate when cranking torque is about to be delivered.

13. The combination, in an engine starter, of a motor, a shell, a shaft passing therethrough and coaxially thereof, a pinion mounted on one of said latter elements, and a friction clutch unit interposed between 100 said shell and said shaft and comprising a nut threaded to said shell, a clutch plate splined to said shaft, a clutch washer interposed between one face of said nut and said plate, a constant torque clutch cooperating with the other face of said nut, and a spring for causing tightening of said first clutch 105 as said spring is distorted.

14. The combination, in an engine starter, of a motor, a rotatable shell, a slidable shaft 110 passing therethrough coaxially thereof, said shell having a driving pinion near its forward end and a shoulder intermediate its ends, a friction clutch unit interposed between said shell and said shaft, and comprising a nut threaded into said shell, a clutch plate splined to said shaft and a clutch washer interposed between one face 115 of said nut and said plate, a coil spring encircling said shaft and interposed between said plate and said shoulder, and a constant torque clutch including a plate splined to said shaft and pressing against the other face of said nut, an annular spring against 120 said plate, and a lock ring encircling the inner periphery of said nut and holding said spring against said plate, for maintaining a constant clutching pressure between said plate and said nut.

15. The combination, in an engine starter, 125

of a shell, the rotor of a motor encircling said shell and secured therefo, a slidable shaft passing through said shell coaxially therewith and bearing a toothed driving member, and shifting mechanism for said shaft threaded to said shell and splined to said shaft.

16. The combination, in an engine starter, of an armature having an internal cylindrical threaded wall, a splined shaft coaxial of said wall and carrying a pinion, a clutch unit interfitting the threads of said wall and the splines of said shaft, and a spring interposed between said unit and said shaft, whereby upon starting of the motor, the shaft will be yieldingly shifted to move said pinion into meshing position, and thereupon said clutch will be tightened to transmit cranking torque.

17. The combination, in an engine starter, of a motor, having an annular armature, end heads for said motor, a driving pinion on the exposed side of one said end head, shifting mechanism for said driving pinion extending through the axial opening in said armature and constituting an armature support, bearings in said end heads for said armature and shifting construction, said shifting construction comprising splines rigid with said pinion, splines rotatable with

said armature and inclined with respect to said splines first mentioned, and a member interfitting both sets of splines, whereby upon starting of the motor the pinion will advance into mesh.

35

18. The combination, in an engine starter, of a motor having an annular armature, end heads for said motor, a driving pinion on the exposed side of one said end head, shifting mechanism for said driving pinion extending through the axial opening in said armature and constituting an armature support, bearings in said end heads for said armature and shifting construction, said shifting construction comprising splines rigid with said pinion and screw threads rigid with said armature, and a clutch unit having a nut co-operating with said screw threads, a clutch plate interfitting said splines, and a friction washer interposed between said nut and said plate; and a spring interposed between said plate and a part rigid with said pinion to push said pinion into mesh by the advance of said clutch unit when the motor is started.

40

45
